DIVIDING STRIP

Samuel C. Awbrey, Kansas City, Mo.

Application February 27, 1935, Serial No. 8,477

12 Claims. (Cl. 94—17)

This invention relates to a dividing strip used in producing patterns in floors, which are formed of a plastic material and then permitted to harden. One of the most common of this type of floor is the terrazzo.

The principal object of this invention is the provision of a dividing strip having tongues stamped therefrom, and which are formed to extend outwardly from the general plane of the strip with their free ends extending into the slots formed in the strip by the removal of the tongues.

Another object of the present invention is the provision of a dividing strip having tongues integral therewith, said tongues being formed and positioned with their free ends positioned transversely in the slots formed by the punching of the tongues from the strip and means for preventing movement of the tongue transversely of the strip.

A further object is the provision of a dividing strip having a tongue stamped therefrom and positioned with its free end extending transversely through the slot formed through the strip.

Other objects are economy and simplicity of construction and ease and efficiency of operation.

With these and other objects in view which will appear during the course of the specification, reference will now be had to the drawing, wherein:

Figure 1 is a fragmentary, perspective view of a dividing strip embodying this invention.

Fig. 2 is a sectional view taken on line II—II of Fig. 1.

Fig. 3 is an enlarged, cross sectional view of the strip positioned in operative position in a floor.

Fig. 4 is an enlarged, fragmentary, perspective view of the strips shown in abutting relation.

Fig. 5 is a fragmentary, perspective view of a modified form of the strip, showing the free ends of the tongues in adjacent relation.

Fig. 6 is a view of a modified form of the strip showing the tongue disposed in the same direction.

Fig. 7 is a perspective view of a modified form of the strip with alternate groups of tongues disposed on opposite sides of the strip.

Fig. 8 is a perspective view of a portion of a modified form of the strip showing the tongues extending through the slots.

Fig. 9 is a longitudinal section taken on line IX—IX of Fig. 8.

Fig. 10 is a modified form of the strip having means for preventing transverse movement of the tongue from the slot.

Fig. 11 is a modified form of the strip showing means for preventing transverse movement of the tongue when positioned in the slot.

Fig. 12 is a sectional view taken on line XII—XII of Fig. 11, and,

Fig. 13 is a perspective view of a modified form of the strip in which means is provided for preventing movement of the tongue longitudinally of the strip.

Throughout the several views like reference numerals designate similar parts and the numeral 20 indicates a strip or bar of metal, having an uninterrupted upper edge 22. While this member 20 is shown as a strip of flat material having its opposite edges parallel, however, it is apparent that it might be made from a bar of any other suitable form. For instance, it might be possible to make the uninterrupted upper edge thicker than the major portion of the strip; also, the strip might be produced by securing together strips of material of different widths.

The form of dividing strip as shown in Figs. 1, 2, 3 and 4 is provided with groups of longitudinally spaced, loop-formed bonding projections 24. Each group consists of two longitudinally disposed loop members formed by stamping tongues 26 from the body of the strip and then bending the tongue outwardly beyond the plane of the strip with the free end 28 thereof projected into slot 30, which is formed in the strip by the removal of said tongue.

It will be observed that the tongues of each group are oppositely disposed and that an opening 32 is formed, through which fastening or anchoring means might be projected to facilitate proper positioning of the strip in certain types of installation. This form of the dividing strip is provided with one face 34 which is free from projections, while the opposite side 36 thereof has the loop-formed binding projections. When laying a floor surface of this type in which it is necessary to use abutting angle strips as shown in Fig. 4, it is apparent that the strip 38 may be positioned at any point along the one side of the continuous strip 40.

Referring to Fig. 3, in which a cross sectional view of the strip in operative position in a floor construction is shown, 42 designates the foundation bed of the floor, while 44 is an intermediate bed of cement, into which the lower portion of the dividing strip is inserted while the same is wet. It will be observed that the tongues are 55

stamped from the lower portion of the strip with their upper edges positioned substantially on the center line, thereby serving as a depth gauge to determine the degree of insertion. Furthermore, 5 these loops, together with the slots, serve as means for binding the strip in the intermediate or under bed of the floor. After the under bed 44 has hardened, the terrazzo or wearing surface 46 is 10 added to a depth such that the upper uninterrupted edge 22 of the strip is flush therewith. This upper surface is then ground and polished to produce a wearing surface with the edges of the strips exposed to form any desired pattern.

In Fig. 5 it will be observed that the free ends 15 of the tongues of each group are in adjacent relation, while in the modified form shown in Fig. 6 the free ends of these tongues are projected in like directions. The groups of bonding projections 48 as shown in Fig. 7 are alternately projected from opposite sides of the strip to produce 20 a uniformly balanced structure.

The principal difference between the modified form shown in Figs. 8 and 9 is the provision of a 25 formed tongue 50 which extends entirely through the slot 52 to produce a bonding projection at both sides of the strip. The tongue 54 which is shown in Fig. 10 is provided with a shoulder 56 at its free end which, when the tongue is in the operative position, serves to prevent outward 30 movement of the tongue from the slot 58. When the tongue is so formed, slot 58 is offset as at 60.

In the modified form shown in Figs. 11 and 12, the tongue is provided with two downwardly projecting portions 62 and 64 which are adapted to 35 be positioned at opposite sides of the strip to preclude any transverse movement of the free end of the tongue when the same is in the operative position.

Referring to Fig. 13, tongue 66 is formed with a 40 downwardly extending portion 68 adjacent its free end which is adapted to be inserted in slot 70 formed in the lower marginal edge of slot 72 to prevent movement of the free end of the tongue 45 in a direction longitudinally of the strip. While the tongue securing means shown in Figs. 10, 11, 12 and 13 have been limited to but one edge of the tongue, however, it is apparent that a like securing means might be provided for the top edge without departing from the spirit of the invention. It will be observed that in all of the forms 50 shown that the free end of the tongue is inserted into or through the slot, thereby producing a very rigid and efficient bonding projection without the necessity of drawing the metal, thus making it 55 possible to produce a very convenient and efficient binding strip of substantially any material that will permit of slight bending.

The tongues shown are all in longitudinal, parallel relation to the strip, however, they might be 60 positioned at any desired angle relative to the strip, also the opening or slot into which the free end of the tongue is projected might be one other than that formed by the stamping of the tongue.

What I claim is:

- 65 1. A dividing strip for terrazzo floors or the like having a tongue carried at its one end by the strip and having its free end projected into a slot formed in said strip.
- 70 2. A dividing strip for terrazzo floors and the like having integral tongues punched therefrom to form slots in the strip, said tongues being formed and positioned with their free ends extending into their respective slots intermediate the ends thereof.

3. A dividing strip for terrazzo floors and the like having its opposite edges substantially parallel and uninterrupted, a tongue punched from the interior of said strip and formed outwardly from the side of said strip with the free end thereof positioned in the slot formed in the strip by the removal of said tongue. 5

4. A dividing strip for terrazzo floors and the like having an uninterrupted upper edge, an integral tongue stamped from the interior of said strip to form a slot therein, said tongue being bent to extend outwardly from the side of said strip with its free end extended into said slot intermediate the ends thereof. 10

5. A dividing strip for terrazzo floors and the like, having an uninterrupted edge; tongues stamped from the interior of said strip, formed to extend outwardly from the side of said strip with the free ends thereof extending through the respective slot formed in the strip by the removal 20 of the tongues.

6. A dividing strip for terrazzo floors and the like having an uninterrupted upper edge; integral tongues punched therefrom to form slots in the strip, said tongues being bent and positioned with their free ends extending through their respective slots. 25

7. A dividing strip for terrazzo floors and the like having an uninterrupted upper edge; integral tongues punched therefrom to form slots in the strip, said tongues being bent and positioned with their free ends extending through their respective slots; and means integral with said tongue to preclude movement of tongue in one direction transversely to said strip. 35

8. A dividing strip for terrazzo floors and the like having an uninterrupted upper edge; integral tongues punched therefrom to form slots in the strip, said tongues being bent and positioned with their free ends extending through their respective slots; and means integral with said tongues to preclude movement of said tongues transversely of said strip. 40

9. A dividing strip for terrazzo floors and the like having an uninterrupted upper edge; an integral tongue punched therefrom to form a slot in the strip, said tongue being bent and positioned with its free end extending through said slot; and a groove formed in the lower margin of said slot adapted to receive one edge of the free end of said tongue to preclude movement of said tongue longitudinally of said strip. 45

10. A dividing strip for terrazzo floors and the like, having a longitudinally disclosed tongue stamped therefrom and shaped to form a loop bonding projection, with its free end positioned in the slot formed by the removal of the tongue from the strip, the upper edge of said tongue being positioned substantially on the center line of 55 said strip. 60

11. A dividing strip for terrazzo floors and the like, having spaced-apart groups of loop bonding projections formed by tongues stamped from said strip, the free end of each of said tongues being 65 positioned in a slot formed in said strip.

12. A dividing strip for terrazzo floors and the like, having an uninterrupted upper edge; longitudinally disposed integral tongues stamped from the lower portion of said strip, bent to form bonding projections at opposite sides of the strip, each of said tongues having its free end extended into 70 a slot formed through said strip. 70
